UNITED STATES PATENT OFFICE.

JOSEPH MORGAN, JR., OF JOHNSTOWN, PENNSYLVANIA.

APPARATUS FOR TILTING LADLES.

SPECIFICATION forming part of Letters Patent No. 366,340, dated July 12, 1887.

Application filed November 1, 1886. Serial No. 217,654. (No model.)

To all whom it may concern:

Be it known that I, JOSEPH MORGAN, Jr., of Johnstown, in the county of Cambria and the State of Pennsylvania, have invented a new 5 and valuable Improvement in the Apparatus for Handling the Ladles Carrying the Iron or Steel in Steel-Works; and I do hereby declare that the following is a full, clear, and exact description of the construction and operation 10 of the same, reference being had to the annexed drawings, making part of the specification, and to the letters and figures of reference marked thereon.

This invention relates to an apparatus, first, 15 for holding the ladle securely in its upright position; second, for altering the inclination of the ladle slightly within a limited movement, to center the pouring-nozzle over the molds; third, for turning it slowly to pour the 20 metal out over the side or lip of the ladle; and, fourth, for turning the ladle completely over or through a rotary motion of about one hundred and eighty degrees to dump out the slag, and for performing all these operations with 25 the greatest safety to the men engaged in directing the ladle and with the greatest possible dispatch.

Prior to this invention ladles have been so arranged that the trunnions or axes of rotation were above the center of gravity of the 30 ladle, in which case the ladle has been tilted from the upright position by a chain attachment operated by a tensile force, or the ladle has been rotated by a worm engaging in a 35 worm-wheel upon the end of the trunnion. The former arrangement is unsafe because it is not sufficiently positive, and the latter is unsafe because, in case the ladle-crane unexpectedly lowers upon the molds, the worm-wheel is disengaged from the worm and the 40 ladle is in danger of being overturned.

By the invention herein described the ladle is held positively in a nearly-upright position, and is rotated at the will of the operator. I 45 attain these objects by the mechanism illustrated in the accompanying drawings, in which—

Figure 1 represents a side elevation of the jib part of a ladle-crane of ordinary construction, with a ladle and its improved manipulating apparatus attached, the ladle being shown in its upright position. Fig. 2 is a plan

of the same. Fig. 3 is a side elevation of ladle and jib, the ladle being turned as in pouring over the lip. Fig. 4 is a side elevation of ladle 55 and jib, the ladle being inverted. Fig. 5 is an enlarged view of the ladle-arm, and Fig. 6 is a transverse section of the same through center of ladle-trunnion and pin *e*. Fig. 7 is an end view of the ladle-arm. Figs. 8, 9, and 10 60 are enlarged views of details of latch-bolt.

Similar letters refer to similar parts throughout the several views.

The letter *s* represents the mast of a ladle-crane; *t* represents the jib, and *u* represents 65 the inclined tie-bars connecting mast and jib and supporting the latter.

The ladle *a* is provided with axes or trunnions *b b*, resting in bearings upon the jib of the crane in the usual manner. Preferably 70 the axes or trunnions should pass through or near the center of gravity of the full ladle, as this makes the manipulating easier.

c is a segment of metal of the form shown in Figs. 1, 3, and 4. The trunnion *b* passes 75 through it, as shown, and it is keyed to the trunnion by key *q*.

m is a metal plate corresponding in form to the segment *c*. This segment *c* and plate *m* constitute the sides of a triangular box, closed 80 at the top and bottom and open at its curved outer periphery, the sides of this box *z* being far enough apart to allow free play within it of the lever *d*. The movable lever *d* is pivoted on the ladle-trunnion and moves within 85 the box *z*, being operated by means of the rod *f*, connecting it to the cross-head on the piston-rod *g* of a hydraulic cylinder and piston, *h*.

The play of this lever *d* within the box *z* would be from the box end *o* to the box end *p*, 90 and when in position at *o*, Fig. 5, a pull (toward the mast) upon it would revolve the box *z*, and when in position at *p*, Fig. 5, a push (from the mast) upon it would revolve the box *z*. It is obvious, however, that the horizontal stroke of the rod *f* will not be sufficient to effect a sufficient revolution of the box *z* and attachments to turn the ladle over and return it, and therefore the removable pin *e* is used in effecting successive partial 95 revolutions, the lever *d* pushing against it in an outward thrust when the lever is in position at *o*, Fig. 5, and pulling against it in a return-stroke when in position at *p*, Fig. 5.

Ordinarily the two relative positions will be sufficient, as shown at Fig. 5. The pin *e* passes through the plate *m* and into the segment *c*, and is an adjustable stop, upon which the lever *d* operates, as described, when desired, and it is carried by suspending the link *k* in such a manner that it can readily be so far drawn out as to allow the shifting of lever *d* within the box *z*, and not to detach it wholly from its orifice in the plate *m*.

The pin *e* may be arranged to pass through the lever *d*, and this lever and box *z* may have more than two relative positions. *i* is a valve to govern the admission and exit of water to and from either end of the hydraulic cylinder *h*. This valve is operated by a man standing upon the platform of the crane in the usual manner. A stop-bolt, *l*, or latch, (shown in detail in Figs. 8, 9, and 10,) placed upon the jib of ladle-crane, if thrown out, engages the cross-head and limits the motion of the piston in the cylinder *h*.

In handling the full ladle, when it is desired to use only a small part of the rotary motion for the ordinary use of centering the ladle over the molds in pouring a heat, this bolt *l* is thrown out. This latch can be thrown out to engage the cross-head or drawn back to clear it at pleasure of the operator, and a part or a full stroke of the piston be used.

The plate *m*, the function of which is to prevent lateral play of the lever *d*, may be dispensed with, and in this case I construct the segment *c* with a rim or flange corresponding to the top and bottom of box *z*. I prefer, however, to use the plate *m*.

The operation is as follows: The ladle being upright, the lever *d* is fastened so that the piston is at the end of its stroke nearest the ladle, and the latch *l* is thrown in to limit the stroke of the piston. By properly operating the valve *i* the ladle can be tilted through the small arc of rotation sufficient to center the pouring-nozzle over the molds in the ordinary operation of pouring through the nozzle, as shown at Fig. 1. If it is desired to pour the metal over the lip of the ladle, the latch *l* is drawn back, and a full stroke of the piston away from the ladle will rotate the ladle about ninety degrees, as shown in Fig. 3, and pour out the metal into molds properly placed. After the metal is all poured out it will be necessary to empty the slag out of the ladle. This slag is adhesive and requires the ladle to be inverted. The ladle in pouring having been tipped ninety degrees and retained in that position by means

of a hinged prop or bar, *n*, as shown in Fig. 3, &c., the pin *e* is withdrawn, a return-stroke of piston toward the ladle is made, the pin *e* is reinserted, fastening the lever *d* in position shown in dotted lines in Fig. 5, a stroke of the piston from the ladle is made, and the ladle is thus inverted, as shown in Fig. 4. These operations are all performed in less time and with more safety than by apparatus previously used.

It is obvious that details of connection of arm *d* and box *z* may be varied somewhat from details shown.

What I claim as my invention, and desire to secure by Letters Patent, is—

1. A ladle - turning arm consisting of a flanged segment fixed to the ladle-trunnion, and a lever adapted to engage this fixed segment and rotate the same, the lever being operated by a hydraulic piston or other power, substantially as described.

2. A ladle - turning arm consisting of a box fixed to the ladle-trunnion, and a lever adapted to move within and rotate this fixed box, the lever being operated by a hydraulic piston or other power, substantially as described.

3. A ladle-turning arm consisting of segment *c*, fixed to the ladle trunnion, and the lever *d*, adjustable upon segment *c* by means of the movable pin *e* and operated by a hydraulic piston or other power, substantially as described.

4. A ladle-turning arm consisting of box *z*, fixed to the ladle-trunnion, and the lever *d*, adjustable within this box by means of the movable pin *e* and operated by a hydraulic piston or other power, substantially as described.

5. The combination and arrangement of the carrying link *k* with the movable pin *e*, box *z*, and lever *d*, substantially as described.

6. The lever *d*, adjusted to engage and turn a box or segment fixed to the trunnion of a casting-ladle, and connected by rod *f* to the piston-rod of a hydraulic cylinder, the stroke of which is regulated by stop - latch *l*, substantially as described.

7. The combination and arrangement of a hydraulic cylinder and ladle with a ladle-turning arm consisting of segment *c*, lever *d*, and removable pin *e*, said lever being operated by the connecting-rod *f* and stop-latch *l*, substantially as described.
